(57) **CLAIM**

The ornamental design for a wheel hub, as shown and described.

DESCRIPTION

FIG. 1 is a front-right-side view of a wheel hub according to an embodiment;

FIG. 2 is a rear-left-side view of the embodiment;

FIG. 3 is a front view of the embodiment;

FIG. 4 is a rear view of the embodiment;

FIG. 5 is a right-side view of the embodiment;

FIG. 6 is a left-side view of the embodiment;

FIG. 7 is a top view of the embodiment; and,

FIG. 8 is a bottom view of the embodiment.

The broken lines depict portions of the wheel hub that form no part of the claimed design.
